VALVE

Frank W. Taylor, Springfield, Mass., assignor to
Westinghouse Electric & Manufacturing Company, a corporation of Pennsylvania

Application December 22, 1931, Serial No. 582,663

2 Claims. (Cl. 230—231)

My invention relates to compressors, and particularly to intake and discharge valves for compressors.

It is an object of my invention to provide compressor intake and discharge valves by means of a plate and two resilient sheet members having movable flaps which are placed adjacent to the plate, one on each side thereof.

It is another object of my invention to provide a compressor valve such as described above so that the aforesaid valve sheets placed on each side of the valve plate are identical, and, therefore, interchangeable, so that only one stamping die is necessary and so that only one kind of valve sheet need be kept in stock.

It is a further object of my invention to provide intake and discharge valves for a compressor which have few moving parts, and which are of exceptionally long life relative to existing valves particularly when utilized in high-speed compressors.

The features of the invention which I believe to be new are particularly pointed out in the appended claims. For a full understanding of the principles of the invention and the best mode of applying the same, reference may be had to the accompanying drawing, in which,

Fig. 1 is a front elevational view of a portion of an assembled compressor containing an embodiment of my invention.

Fig. 2 is a top plan view of the compressor shown in Fig. 1.

Fig. 3 is a sectional view, taken on line III—III of Fig. 2, illustrating a portion of a compressor embodying my invention, and

Fig. 4 is an exploded perspective view of the compressor shown in Fig. 1, showing in the order of assembly the various parts of the compressor which are utilized in my invention.

In order to accomplish the objects of my invention, a compressor is essentially constructed in the following manner. A valve plate is disposed between the compressor head and cylinder, and is provided with intake and discharge ports. Two interchangeable resilient sheets having resilient flaps and port apertures cut therein are disposed adjacent to the valve plate, one on each side thereof, with the resilient flaps and port apertures properly arranged with respect to the inlet and discharge ports of the valve plate, so that the ports of the valve plate which connect with the high and low pressure sides of the compressor are opened or closed in response to conditions within the compressor, namely, suction or discharge of the compressor.

The improved form of the compressor head and valve plate, and the preferred form of valve discs which are utilized in my invention are described and claimed in the application of Frank Conrad and Christian Aalborg, for compressors, Serial No. 581,260, filed December 15, 1931, and assigned to the assignee of the present application.

Referring specifically to the drawing for a detailed description of my invention, numeral 2 designates generally a compressor comprising a cylinder 3, a piston 4, a valve plate 5, a head 7, intake conduits 9 and a discharge conduit 11.

The valve plate 5 comprises a substantially flat preferably metallic plate provided with lateral intake passageways 13, to which are connected 15 the intake conduits 9. An intake port 15, extending from the lower surface of the valve plate 5 to a point about halfway through the plate, connects with the intake passageways 13 to form the low pressure side of the compressor. A discharge port 17 extends completely through the valve plate 5. Screw holes 21 are provided in the plate 5 to facilitate assembly with the other parts of the compressor.

An upper valve disc 23 and a lower valve disc 24 are disposed on each side of the valve plate 5 and are provided with resilient flaps 25 and 26, respectively, and port apertures 27 and 28, respectively. The discs 23 and 24 are identical and, therefore, interchangeable. The directions of the flaps 25 and 26 are reversed in assembly, as shown in Figs. 2 and 4, and the port aperture 27 in the upper valve disc 23 is not utilized in this embodiment of my invention. The flaps 25 and 26 are so disposed as to overlap the ports 17 and 35 15, respectively, when assembled.

Rivet holes 33, 31, 19, and 30 are provided in the stop member 29, the upper disc 23, the valve plate 5 and the lower disc 24, respectively, and rivets 35 hold the above members together. The above members are assembled before being disposed in the compressor 1.

The head 7 of the compressor 1 is provided with a hollow raised portion 40 on the top thereof for receiving compressed gas, and an aperture 10 is provided in the head 7 which connects with the discharge conduit 11. The head 7 and cylinder 3 are provided with tapped holes 37 and 39, respectively, and bolts 41 extend through holes 37 and 39 as well as through holes 21 in the valve plate 5. The bolts 41 are utilized to assemble the cylinder 1 after the resilient discs 23 and 24 and the stop member 29 are attached to the valve plate 5.

The operation of the compressor is as follows:

on the suction stroke of the piston 4, the flap 26 of the lower valve disc 24 is pulled downwardly because of the partial vacuum present in the cylinder 3 on the suction stroke. Gas, therefore, enters the cylinder 3 through the intake conduits 9, and passageways 13 and intake port 15 in the valve plate 5. At the same time, the resilient flap 25 of the upper valve disc 23, which overlaps the discharge port 17, is pulled tightly against the valve plate 5, thus closing the port tightly so that medium is not drawn from the high pressure side of the compressor on its suction stroke.

On the compression stroke of the piston 4, the flap 26 in the lower disc 24, which overlaps the intake port 15, is forced against the valve plate 5 by pressure of the medium being pumped, thus closing the intake port 15 so that medium is not forced into the low pressure side of the compressor. The medium which is compressed passes through the discharge port 17, raises the flap 25 of the valve disc 23 and passes into the raised portion 7 of the head 3 and through the aperture 10 and conduit 11 in the head 3. The stop member 29 limits the upward movement of the flap 25 of the valve disc 23.

From the foregoing description and drawing, it will be readily seen that I have provided a simple and efficient compressor valve which utilizes identical resilient sheets with movable flaps on each side of a valve plate having intake and discharge ports therein.

While I have shown my invention in but one form, it will be obvious to those skilled in the art that it is not so limited, but is susceptible of various changes and modifications, without departing from the spirit thereof, and I desire,

therefore, that only such limitations shall be placed thereupon as are imposed by the prior art or as are specifically set forth in the appended claims.

What I claim is:

1. In a fluid translating device, the combination of a cylinder, a cylinder head, a valve plate disposed between the cylinder and cylinder head and having flat surfaces on opposite sides thereof, said valve plate having an inlet port extending from the periphery of the plate into one of said flat surfaces, and sheet valve members lying against said respective flat surfaces, said valve members including portions retained in fixed relation against the flat surfaces and movable flap portions cooperating respectively with said inlet and outlet ports to form inlet and discharge valves, the valve member embodying said inlet valve having an aperture therein in registry with the outlet port.

2. In a fluid translating device, the combination of a cylinder, a cylinder head, a valve plate disposed between the cylinder, and the cylinder head and having flat surfaces on opposite sides thereof, said valve plate having an inlet port extending from the periphery of said plate into one of said flat surfaces and an outlet port opening into both of said flat surfaces, and valve members disposed on either side of said valve plate, said valve members including portions retained in fixed relation against the flat surfaces and movable flap portions cooperating respectively with said inlet and outlet ports to form inlet and discharge valves.

FRANK W. TAYLOR.
